HAIR WAVING APPARATUS

Filed July 31, 1928

INVENTOR.

INVENTOR.
Arthur G. Borden,
BY John B. Brady
ATTORNEY

UNITED STATES PATENT OFFICE

ARTHUR G. BORDEN, OF WASHINGTON, DISTRICT OF COLUMBIA, ASSIGNOR TO THE BORDEN METHOD, INC., OF WASHINGTON, DISTRICT OF COLUMBIA, A CORPORATION OF DELAWARE

HAIR-WAVING APPARATUS

Application filed July 31, 1928. Serial No. 296,537.

My invention relates broadly to hair waving apparatus and more particularly to a construction of casing for the heater employed in hair waving operations.

One of the objects of my invention is to provide a construction of heater for use in hair waving apparatus having a casing capable of remaining at a relatively low temperature independently of the relatively high temperature to which the heating element within the hair waving apparatus may be raised.

Another object of my invention is to provide a practical construction of casing for a heater employed in a hair waving apparatus where the parts of the casing may be molded inexpensively on a quantity production basis and connected one with respect to the other for providing a substantially shell-like enclosure for a heating element, protecting the patron and operator against burns due to high temperature.

Still another object of my invention is to provide a construction of casing for an electric heater for hair waving in which a casing of shell-like construction is provided, with ventilating means disposed in one portion of the shell-like casing, the casing having means for interconnecting the portions thereof to provide a heat-resisting enclosure.

A still further object of my invention resides in the construction of a casing for hair waving apparatus, wherein the heater member is in the form of a cylindrical device, with means for preventing the leakage of condensate from the casing, thereby preventing injury to a patron during a hair waving operation.

Other and further objects of my invention reside in the construction of a casing for a hair waving apparatus in which the casing is formed in two parts related one to the other for compactly housing a heater member, as more fully set forth in the specification hereinafter following by reference to the accompanying drawings in which:

Figure 1 is a side elevation of the hair waving apparatus of my invention; Fig. 2 is a vertical cross-sectional view taken through the hair waving apparatus of Fig. 1; Fig. 3

is a cross-sectional view of the parts of the casing in disassembled position preparatory to an assembly operation; Fig. 4 is a cross-sectional view taken through the heater and casing on line 4-4 of Fig. 2; and Fig. 5 is a cross-sectional view taken through the hair waving apparatus on line 5-5 of Fig. 2.

Referring to the drawings in detail, reference character 1 designates the upper portion of the shell or casing which provides the enclosure for the hair waving apparatus of my invention, with the lower portion of the shell represented at 2 and provided with screw threads 4 formed on the annular portion 5 of the shell 2 which cooperates with the internal screw threads 3 of the shell 1. In the upper end of the shell 1 there is provided an annular portion 6 which terminates in a head portion 7 with an aperture 8 therein.

This cone shaped undersurface acts as a guide for rod 24 making insertion of rod 24 in aperture 8 quick and positive. The aperture 8 holds rod 24 exactly in upper portion of the heating chamber. The cone shaped head 7 forms a closed steaming tube after rod 24 is inserted in aperture 8. A slightly larger diameter to aperture 8 over diameter of rod 24 allows for the necessary escape of the steam. The casing 1 is provided with offset portions 9 and 10 on diametrically opposite sides of the casing which serves as entrances for the conductors which connect with the electric heater enclosed by the casing. The shells 1 and 2 are molded from insulated material which offers large resistance to heat. The lower extremity of the shell 2 is provided with an inturned flange 11 which is shaped at 12 in such manner as to support the cylindrical heater structure 15.

The electric heater shown at 15 may be formed in any desired manner. I have illustrated the turns 14 of resistance wire embedded in a suitable refractory or heat-resisting material shown at 16 and forming heating means between the walls of the cylindrical member 15. A ring member 30 is positioned interiorly of the casing 1 and provides an abutment against which the upper extremity of the cylindrical member 15 contacts. The heater structure is assembled as

shown. I have shown conductors 21 and 22 passing through the entrances 9 and 10 and secured at 19 and 20 interiorly of the casing 1 and connecting with the resistance wire 14 forming the electric heater. In order to maintain the surface of the heat-resisting shell portions 1 and 2 at a low temperature, I provide ventilating ports 23 in the casing 1, as shown in the drawings. A central rod 24 which is secured to plate member 25 in the lower portion of the heater provides a guide on which the hair of the patron is wound during a hair waving operation. The plate member 25 has a plurality of heat-resisting projections 26 thereon which connect to heat-resisting plate member 27 which is covered on its lower surface by means of a pad represented at 28. An aperture formed in pad 28 and in plates 27 and 25 permits the strands of hair represented at 29 to be passed into the heater and locked in position by rotative movement of the plate member 31 by rotatively moving the plate 31 by grasping the projecting lug 31^a and shifting the lug with respect to the lug 25^a. In order to prevent any dripping of condensate from the heater, I provide a plurality of absorbent gaskets 32 positioned on the plate member 31 as shown. The strands of hair are wrapped upon the central rod 24 by means of the heat-resisting winder member shown at 33. This winder is set forth in more detail in my co-pending application Serial No. 263,493, filed March 24, 1928, for permanent hair waving appliance. A wrapper is provided as represented at 34 for holding the necessary softening solution for steaming and protecting the hair against excessive heat, and a clamp having a pair of arms represented at 35 secures the wrapper in place. The clamp 35 is provided with a bridge member 36 at the upper extremity thereof through which the central rod 24 passes. This clamp holds the wrapped assembly exactly in the center of the heating tube and also holds the lower portion of shell firmly against plate 31. This clamp 35 allows easy and instant withdrawal of the heating element and attached casing from the hair without injury to the patron.

It will be observed that the heater is not in any sense locked to the head, which is prohibited by law in several States. By simply lifting the shell the entire assembly and clamp is withdrawn from the heating element so that the patron may readily draw away from the heater without injury to the hair.

The spring tension obtained by operation of spring 35 permits the assembly shown in Fig. 2 to be maintained in exact central position within the heater and held firmly against plate members 25 and 31 at bottom.

I have found the construction illustrated herein to be extremely practical, and while I have described my invention in one of its

preferred embodiments, I desire that it be understood that modifications may be made and that no limitations upon my invention are intended other than are imposed by the scope of the appended claims.

What I claim as new and desire to secure by Letters Patent of the United States is as follows:

1. In a hair waving apparatus a cylindrical heater member, a casing comprising a pair of sections screw threaded one into the other, one of said sections having means for supporting said cylindrical heater in position within said casing, and means for maintaining hair in wrapped formation within said heater for treatment therein. 70

2. In a hair waving apparatus a tubular heater member, a casing comprising a pair of sections substantially enclosing said heater, said sections being divided laterally at the length thereof and screw threaded one into the other, and means carried by the end of one of said sections for supporting said tubular heater member in a position whereby hair in wrapped formation may be subjected to heat treatment within said apparatus. 90

3. In a hair waving apparatus, a tubular heater member, a casing comprising a pair of sections arranged to be inserted over opposite ends of said tubular heater member, one of said sections having a substantially annular trough at the lower extremity thereof for providing a seat for said heater member, said sections being connected one to the other intermediate the ends of said heater member. 95

4. In a hair waving apparatus a tubular heater member, means for securing hair in wrapped formation within said tubular heater member, a casing having a pair of independent sections screw threaded one into the other, the lower section being provided with an inwardly directed annular flange for providing a trough positioned to receive one end of said tubular member. 105

5. In a hair waving apparatus, a tubular heater member, means for securing hair in wrapped formation within said tubular heater member, a pair of casing members positioned over opposite ends of said tubular member and connected centrally one to the other, said casing members being positioned immediately adjacent said tubular member at the opposite ends thereof and extending outwardly from said tubular member intermediate the ends thereof, with the area intermediate the interior walls of said casing members and the exterior surface of said tubular member apertured for the ventilation of the area intermediate said heater and the interior walls of said casing. 115

6. In a hair waving apparatus, a tubular heater member, means for securing hair in wrapped formation within said tubular heater member, a pair of independent casings 120

screw threaded one into the other intermediate the length of said tubular member, one of said sections having an inturned annular flange providing a support for the end of

5 said tubular member, the upper portion thereof forming a guide for centering said rod within said heater member and forming a closed steaming tube for the heater member and hair.

10 7. In a hair waving apparatus, a tubular heater member, means for securing hair in wrapped formation within said tubular heater member, a casing comprising a pair of heat-resisting members having a substantially larger diameter at one end than at the other end, the ends of the larger diameter being screw threaded one into the other, the lower section having an inturned annular flange for supporting said heater in a position within

20 said heat-resisting members.

15 8. In a hair waving apparatus, a tubular heater member, means for securing hair in wrapped formation within said tubular heater member and a heat-resisting casing comprising a pair of cooperating sections enclosing said heater member, said sections having adjacent portions thereof displaced from the walls of said heater member for substantially preventing the conduction of heat to the

25 exterior of said casing and the opposite end portions thereof embracing the ends of said tubular heater member.

30 9. In a hair waving apparatus, a tubular heater member, means for securing hair in wrapped formation within said tubular heater member, a casing composed of heat-resisting material, said casing being constructed of a pair of independent sections insertable over opposite ends of said heater, said sections being substantially enlarged intermediate the ends of said tubular heater member for displacing the walls of said casing from the heater member.

35 10. In a hair waving apparatus, a tubular heater member, means for securing hair in wrapped formation within said tubular heater member, and a pair of heat-resisting members insertable over opposite ends of said heater and connected intermediate the ends of said heater member, said heat-resisting members being enlarged intermediate the ends thereof for providing an air space between said tubular heater member and the interior walls of said heat-resisting members,

40 45 50 55 60 65 70 75 80 85 90 95 100 105 110 115 120 125 130

ing from a relatively large central diameter to relatively smaller diameters at opposite ends thereof.

In testimony whereof I affix my signature.

ARTHUR G. BORDEN.
